ELECTRIC SNAP SWITCH

Robert H. Bentley, Hartford, Conn., assignor to
 The Arrow-Hart & Hegeman Electric Company,
 Hartford, Conn., a corporation of Connecticut

Application May 7, 1937, Serial No. 141,372

4 Claims. (Cl. 200—67)

This invention relates to electric snap switches of the lever-operated type though the principles of the invention may be applied to switches operated by push buttons or other types of operating means.

It is an object of my invention to provide an improved electric snap switch having a novel combination of parts which may be inexpensively manufactured and easily fabricated to provide a switch of positive operation and sturdy construction. Other objects and advantages of my invention will become apparent as it is described in connection with the accompanying drawing.

In the drawing, Figure 1 is a side elevation view of an electric snap switch embodying the principles of my invention;

Figure 2 is a side elevation view of the switch shown in Figure 1 but with one of the side insulating plates removed to show the interior mechanism;

Figure 3 is a view similar to Figure 2 but with the parts of the switch in an intermediate position, prior to snapping from "off" to "on" position;

Figure 4 is a section view taken transversely through the switch mechanism along line 4—4 of Figure 2;

Figure 5 is a vertical section view through the switch shown in Figure 1 with the section being taken along 5—5 of Figure 3.

Referring to the drawing the supporting means for the switch mechanism comprises a pair of identical insulating blocks 10 and 12 mounted in spaced relation between parallel insulating plates 14 and 16 and secured thereto by any suitable means. These plates may be recessed as at 14^a to allow movement of the switch parts. Also mounted between the insulating plates 14 and 16 is a third insulating block 13 positioned along the lower edge of the insulating plates 10 and 12 and secured thereto in any suitable manner. The adjacent portions of the insulating blocks 10, 12 and 13 are cut back and recessed to provide a T-shaped chamber 15, in the bottom of which is received a bowed leaf spring 17 whose purpose will be hereinafter described. If desired, several of these insulating parts may be integrally formed. As will be noted in the drawing the end of the leaf spring 17 rests upon the upper or inner surface of the insulating block 13 forming the floor of the chamber 15. In forming and positioning the insulating blocks 10 and 12 parallel side faces 10^a and 12^a are provided in spaced relation to form guide surfaces for the side plates

of a movable carriage designated generally by the numeral 20.

The carriage 20 may be formed of parallel metal side plates 22 and 24 which are maintained in spaced relation by engagement with, or attachment to, narrow parallel end plates 26 and 28. A convenient means of engagement between the plates 22 and 24 and the end plates 26 and 28 may be by the provision of pairs of spaced lugs, such as 22^a and 22^b, projecting from the side edges of the plates 22 and 24 and fitting snugly within openings provided in the end plates 26 and 28. The carriage 20 is adapted to slide within the space between the insulating blocks 10 and 12 while being engaged with and guided by the parallel surfaces 10^a and 12^a of those insulating blocks. To further guide the sliding motion of the carriage 20 parallel grooves 14^c and 16^c may be provided in the inner surfaces of the side insulating plates 14 and 16 for the reception of the parallel side edges of the end plates 26 and 28. The bottom or the innermost edges of the side plates 22 and 24 which are preferably made arcuate to minimize friction are engaged by the spring 17 which thus tends to bias the carriage 20 upwardly.

The top or outer surfaces of the side plates 22 and 24 are provided with identical V-notches, such as 22^v, in the apex of which is pivotally supported a switching member, designated generally by the numeral 30. This switching member is generally of U-shape and embraces the side plates 22 and 24 of the carriage and has its transverse portion 32 passing through apertures, such as 22^c, provided near the lower edge of the plates and of such area as to permit the oscillation of the switching member. In order to permit insertion of the switching member in the apertures 22^c a passage 22^p is cut to the outer edge of each side plate. The transverse portion 32 of this switching member is extended beyond the sides thereof providing extensions 32^a and 32^b for engagement of the fixed switch contacts 40 and 42 hereinafter more fully described. The switching member thus is a movable bridging contact, but obviously it could be employed as a contact mover or carrier instead.

For the purpose of pivotally mounting the switching member, oppositely directed inward extensions or trunnions 34 are provided on the ends of the parallel legs of the switching member. These trunnions 34 engage with the apices of the notches in the side plates 22 and 24.

For the purpose of influencing the movement of the switching member, a flat strut 58 is posi-

tioned between the side plates of the carriage 22 and 24 and is guided in its movement by sliding engagement with the faces of said plates. One end of this strut engages with the inner 5 edge of the transverse portion 32 of the switching member. The other end of the strut is engaged by the end of a manual operating member 52 which is pivoted upon pin 54 passing through and mounted in the side insulating 10 plates 14 and 16 of the switch. An insulating handle 56 is provided on the end of the manual operating member in the usual fashion. Oscillatory movement of the manual operating member is limited in any suitable fashion, such as 15 by engagement of the member with the insulating blocks 10 and 12.

For the purpose of reducing friction, cooperating arcuate surfaces are provided for engagement between the strut 50 and the manual operating member. A similar arcuate surface is provided on the lower end of the strut which engages with the switching member.

From the foregoing description the operation of the switch may now be understood. Assuming the switch to be in the "off" position as illustrated in Figure 2, the handle 56 may be grasped and oscillated in a counter-clockwise direction into the position as shown in Figure 3. In coming into this position the strut 50 has 20 moved to the right and forced the carriage 20 downwardly against the stress of the spring 17 by reason of the force from the strut being transmitted to the carriage through the switching member. Movement any further in a counter-clockwise direction by the handle will cause the parts to pass through a critical or dead-center position and the force of the spring 17 will then cause the switching member to move with a snap action into the closed-circuit position as 30 shown in Figure 1. In this position the carriage will again have risen to the position in which it is shown in Figure 2.

It will be observed that due to the reciprocating movement of the carriage 20 the switching member moves rectilinearly downwardly against the effort of the spring 17 until the dead center position of the parts is reached. At that time the switching member starts to move to its new position and in so doing moves along a curved 40 path as it swings about its pivotal mounting in the carriage while the carriage is simultaneously being pressed up to its original position by the spring 17. The path of movement of the movable contact surfaces is illustrated by 45 dotted lines P in Figure 1. The reverse movement of the movable contact is accomplished when the switch is snapped from "on" (full lines, Fig. 1) to "off" (dotted lines, Fig. 1) position. Thus, the movable contact surfaces of the 50 switching member have a wiping action when coming into engagement with the fixed contacts. A valuable feature of my invention is the wiping action tending to keep the contact surfaces always clean and bright.

60 In order to accommodate the unusual movement of the movable switch contact the fixed contacts 40 and 42 are flared outwardly at their lower edges as may best be seen in Figure 5.

These fixed contacts may be made of resilient sheet metal and secured to the outside surfaces of the side plates 14 and 16 in any suitable fashion. In the embodiment of the invention shown in the drawing there are terminal plates 41 and 5 43 connected with or attached to the fixed contacts but obviously the contacts and terminal plates may be varied in construction.

Many modifications within the scope of my invention will occur to those skilled in the art. 10 Therefore I do not limit myself to the specific form of the invention as illustrated in the drawing.

I claim:

1. In an electric switch, rectilinearly movable 15 supporting means, a movable contact pivotally mounted on said supporting means, a leaf spring engaging and biasing said supporting means in a position to maintain said contact in one or another of two positions, manually operable 20 means for operating the switch, an incompressible member connecting said manual means and said contact, said supporting means moving in response to movement of said manual means and in opposition to said bias for causing movement 25 of said contact to a new position with a snap when said supporting means reaches the limit of its bias-opposing movement.

2. In an electric switch, an insulating base, 30 a carriage rectilinearly slidable therein, a movable contact pivotally mounted on said carriage, an operating lever, rigid means connecting said lever and movable contact, and leaf spring biasing means engaging a curved portion of said carriage whereby said switching member is moved 35 with a snap action after predetermined movement of said lever.

3. In an electric switch, an insulating base, a rectilinearly slidable carriage comprising parallel plates joined at their side edges by bearing 40 plates, a yoke pivotally mounted on said carriage and having contact surfaces, a pivoted manual operating member, a non-compressible member pivotally connecting said operating member and said yoke and positioned between 45 said parallel plates to be guided thereby, resilient means acting on said carriage and compressible to cause operation of said yoke with a snap, fixed contacts engageable and disengageable by said contact surfaces with a combined rotary 50 and rectilinear motion to keep the contact surfaces clean and prevent sticking.

4. In an electric switch, an insulating base, 55 a rectilinearly slidable carriage comprising parallel plates joined at their side edges by bearing plates, a yoke having lateral bearing extensions adapted to be seated in V-notches provided in said parallel plates, a pivoted manual operating member, a non-compressible member pivotally connecting said operating member and said yoke 60 and positioned between said parallel plates to be guided thereby, resilient means acting on said carriage and compressible to cause operation of said yoke with a snap, fixed contacts engageable and disengageable by said contact surfaces with a combined rotary and rectilinear motion to keep the contact surfaces clean and prevent sticking.

ROBERT H. BENTLEY.
